United States Patent Office

Des. 223,574
Patented May 9, 1972

223,574

FISHERMAN'S TOOL

Harry Pittis, 3706 Harrison St. NW,
Washington, D.C. 20015

Continuation-in-part of design application Ser. No. 14,596,
Nov. 22, 1968. This application July 8, 1970, Ser.
No. 21,109

Term of patent 14 years

Int. Cl. D22—05

U.S. Cl. D22—31

FIG. 1 is a side view of one form of the fisherman's tool in open position,

FIG. 2 is a side view of the tool in closed position,

FIG. 3 is a top view of the tool shown in FIG. 1,

FIG. 4 is an end view of said tool,

FIG. 5 is a side view of a modified form of the tool, shown open,

FIG. 6 is a side view thereof in closed position,

FIG. 7 is a top view, and

FIG. 8 is an end view.

This application is a continuation-in-part of design patent application Ser. No. D 14,596, filed Nov. 22, 1968 and now abandoned.

I claim:

The new and ornamental design for a fisherman's tool, as shown and described.
